UNITED STATES PATENT OFFICE

138,322

DESIGN FOR AN ACTUATOR HANDLE

Joseph F. Melichar, Cleveland, Ohio, assignor to
The Parker Appliance Company, Cleveland,
Ohio, a corporation of Ohio

Application March 22, 1944, Serial No. 113,003

Term of patent 14 years

(Cl. D26—1)

To all whom it may concern:

Be it known that I, Joseph F. Melichar, a citizen of the United States, residing at Cleveland, in the county of Cuyahoga, State of Ohio, have invented a new, original, and ornamental Design for an Actuator Handle, of which the following is a specification, reference being had to the accompanying drawing, forming part thereof.

In the drawing:

Figure 1 is a perspective view of an actuator handle looking toward the front, bottom and one side and showing my new design.

Figure 2 is a top plan view of the handle.

Figure 3 is a perspective view of the handle

looking toward the front end thereof, the top and the side thereof opposite the side illustrated in Figure 1.

Figure 4 is a front end elevation of the handle.

The characteristic features of my design reside in the actuator handle of the configuration shown having the frusto-coniform body with the side ribbed short pointer projecting radially from one side thereof and the flared long wing projecting diametrically oppositely to said pointer all as illustrated.

I claim:

The ornamental design for an actuator handle, as shown and described.

JOSEPH F. MELICHAR.
